Primary Examiner — April Rivas(74) *Attorney, Agent, or Firm* — J. Andrew Reed; Vincent J. Allen; Carstens & Cahoon, LLP(57) **CLAIM**

The ornamental design for a tackle backpack, as shown and described.

DESCRIPTION

FIG. 1 is a front elevation view of the tackle backpack;
FIG. 2 is a rear elevation view of the backpack;
FIG. 3 is a left side elevation view of the backpack;
FIG. 4 is a right side elevation view of the backpack;
FIG. 5 is a top view of the backpack;
FIG. 6 is a bottom view of the backpack;
FIG. 7 is a left side perspective view of the backpack; and,
FIG. 8 is a right side perspective view of the backpack.
The broken lines illustrate portions of the tackle backpack and form no part of the claimed design.
